SEALING RING

Frank B. Allen, Lower Merion Township, Montgomery County, Pa., assignor to The Allen-Sherman-Hoff Company, Philadelphia, Pa., a corporation of Pennsylvania

Application May 17, 1932, Serial No. 611,865

4 Claims. (Cl. 103—111)

This invention relates to means for effecting a seal between relatively moving parts, and more particularly to sealing rings for centrifugal pumps which are intended to be used for pumping fluids 5 containing abrasive or otherwise harmful substances.

In the construction of centrifugal pumps for handling liquids containing abrasive materials such as ashes, sand or the like, it has been proposed to provide a supply of clear flushing water to the pump and to cause this clear flushing water to enter the main pumping chamber through the clearance spaces between the rotating pump impeller and the stationary side 10 plates of the pump, thus preventing the entry of abrasive material into these spaces and thereby maintaining the initial high efficiency of the pumping unit as well as materially reducing the depreciation of certain parts of the pump which 15 would otherwise result from the abrasive action 20 of the material pumped.

In practice it was found in order to produce the result above described, with a reasonably small amount of sealing water, it was necessary 25 to maintain the clearances between the rotating element and the stationary portions of the pump extremely low. Great difficulties resulted in that should the plane of rotation of the moving element be not exactly true with the plane of the 30 various registering surfaces, the clearance between would markedly vary. Then, it was either necessary to largely increase the amount of sealing water otherwise required, or the apparatus 35 would fail to function and abrasive material would leak back into the clear water spaces. Even though the pump has been manufactured accurately and functioned perfectly during the life of the original impeller, yet after the first impeller had worn out and a second impeller was 40 installed, a very slight variation in that impeller from the first impeller would result in the difficulties above described.

It is among the objects of my invention to provide means for definitely sealing these slip joints 45 or clearance spaces between the impeller and the pump housing which will permit of the flow of clear flushing water into the pumping chamber, yet will automatically compensate for any reasonable variation in the distance between the stationary portion of the pump and the rotating element at any portion of its rotation, thus guaranteeing a constant and minimum clearance under all conditions of operation.

Other objects of my invention are: the provision 55 of an improved type of sealing ring for

centrifugal pumps; the provision of a sealing ring of the type described which is self-adjusting and self-compensating either because of variation in the spaces between the rotating element and stationary element or because of wear of the registering surfaces; provision of a sealing ring and mounting therefor which will minimize wear upon the ring or upon the element which it engages by automatically providing a film of clear water between these parts; the provision of an improved 10 mounting for the sealing rings of centrifugal pumps which facilitates assembly and adjustment of the pump.

The above and other objects of my invention will appear from the following description of 15 several forms thereof, reference being had to the accompanying drawing, in which—

Figure 1 is a side elevation, partly in section, of a horizontal centrifugal pump equipped with 20 my improved sealing devices.

Figure 2 is an enlarged fragmentary sectional view of the sealing ring, illustrated in Figure 1, which is adapted to seal the joint between the outer periphery of the impeller and the pump 25 housing.

Figure 3 is an enlarged fragmentary sectional view of the sealing ring shown in Figure 1, which is particularly adapted to seal the joint between the inner periphery of the impeller and the pump intake.

Figure 4 is a view generally similar to Figure 3 but illustrating a sealing ring which is maintained in sealing engagement with the impeller by spring means.

Figure 5 is a view similar to Figure 3, illustrating a modified form of sealing ring at the inner periphery of the impeller.

Figure 6 is a view similar to Figure 2 but illustrating a modified form of sealing ring for the joint at the outer periphery of the impeller.

Figure 7 is a sectional view of the sealing ring illustrated in Figure 3 and showing the grooves which assist in the formation of a lubricating film between the sealing ring and pump.

Figure 8 is a view generally similar to Figure 2 45 but illustrating a modified form of my improved sealing ring.

Figure 9 is a fragmentary view of sealing ring installation in which sealing rings of the general type shown in Figures 1 and 2 are mounted in 50 the impeller.

Referring now to Figure 1, the centrifugal pump illustrated is of the horizontal type and includes a shaft 1, at one end of which is mounted 55 the main impeller 2. The shaft 1 is suitably sup-

ported in bearings (not shown) and the impeller 2 rotates within the housing 4. The shaft sleeve 3 passes through a packing gland 3a. An inlet 5 is adapted to conduct the fluid to be pumped into 5 the housing 4, where it is thrown out by the impeller blades 6 into the volute 7 from whence it passes into a suitable discharge pipe (not shown). The impeller 2 includes a plurality of radially extending main blades 6 which extend across between the discs 8 and 9. Auxiliary impeller blades 10 and 11 are formed or secured to the outside of the discs 8 and 9 and are adapted to rotate in the auxiliary pumping chambers 12 and 13 which are formed between the housing 4 and the discs 8 and 9. Auxiliary chamber 12 is disposed on suction side of the pump, i. e., the side of the pump adjacent the inlet pipe 5. Clear flushing water may be supplied to the auxiliary chambers 12 and 13 through the pipe 14 and its branches 15 and 16. 10 To assist in preventing the flow of the fluid being pumped from the main pumping chamber or volute 7 back into the auxiliary chambers 12 and 13, I have provided the sealing rings 17 and 18. Grooves 19 are formed in the side walls of 15 the housing 4 and provide seats for the inwardly extending portions 20 of the sealing rings 17 and 18. The cross-sectional contour of the sealing rings 17 and 18 is best seen in Figure 2, which clearly shows the inner portion 20 of the ring seated in the groove 19 and the thickened outer portion 21 in position with its sealing face 22 bearing against the side of the impeller disc 8. The sealing rings 17 and 18 are preferably made of molded rubber or other suitably resilient and 20 elastic material. To install them in position in the grooves 19 they are stretched over the lips 19' of the groove 19 and, before the pump is assembled and the impeller placed in position, the rings assume the position shown in dotted lines in Figure 2. Thus, it will be seen that the inherent resiliency of the material of which the rings are constructed will tend to maintain the sealing face 22 in contact with the side of the impeller even though the face 22 may be considerably worn 25 away during operation of the pump. When the pump is in operation a lubricating film of water will be formed between the face 22 of the ring and the impeller.

The housing 4 is so formed that an annular passage 23 connects the main pumping chamber with an enlarged annular chamber 24 disposed behind the sealing rings 17 and 18. With this construction it will be seen that when the clear flushing water pressure is increased by the auxiliary impeller blades 10 and 11 to a point greater than the pressure within the main pumping chamber 7, flushing water will flow through the joint between the face 22 of the sealing ring and the impeller discs 7 and 8. If, however, the pressure within the main pumping chamber becomes greater than that within the auxiliary chambers 25 of the sealing rings 17 and 18 tending to force the sealing faces 22 into closer engagement with the impeller discs. Thus, the most effective seal is provided at the time when it is most needed.

At the inner end of the inlet 5 I have provided a sealing ring 26, preferably of rubber or other material of similar characteristics, which is supported for free axial movement in a suitable groove in the inner end of the inlet pipe 5. To maintain the ring 26 (see Figure 3) in sealing contact with the face 8' of the impeller 8, I have 30 provided a plurality of circumferentially spaced

holes 27 which extend from the groove in which the ring 26 is seated into the auxiliary chamber 12. Thus, the pressure of the flushing liquid which enters the chamber 12 is applied to maintain the ring 26 in sealing position. The ring 26 is preferably formed with lips 26' which may be forced out into sealing contact with the walls of the groove by the flushing liquid pressure, thus preventing undesirable leakage past the sides of the sealing ring. Small grooves 26'' are preferably cut in the contact face of the ring 26 to allow of lubrication between the ring and the rotating element. 5 10

The sealing rings illustrated in Figures 1, 2 and 3 which have been just described are mounted in the housing in the pump, but, if desired, these rings may be mounted on the impeller and adapted to rotate therewith. Such an installation is shown in Figure 9. In this view the sealing ring 50 is supported in a suitable groove in the impeller 20 side disc 51 and has a sealing face which engages the housing 52. This ring 50 is preferably cut away as at 53 so that the fluid pressure within the main pumping chamber may be effective to assist in holding the ring in sealing engagement with the housing. It will be understood that this ring is preferably so formed that its inherent resiliency also tends to hold it in sealing position. The ring 54 which is adapted to seal the joint between the inner periphery of the impeller and the 30 housing is generally similar to the ring 26 but is mounted in a suitable groove 55 in the impeller. The side of the sealing ring 54 opposite its sealing face is exposed to the pressure within the auxiliary flushing liquid chamber 56 through the 35 hole or holes 57 and thus the pressure of the auxiliary water is effective to maintain the ring in sealing position.

In Figure 4 I have illustrated a modified arrangement in which the sealing ring 26a is disposed in a relatively deep groove in which are a plurality of springs 27' adapted to keep the ring in sealing contact with the inner periphery of the impeller 2. Rings of this type mounted in this manner may also be used in place of rings 17 and 18 to seal the joint between the outer periphery of the impeller and the housing. 40 45

Figure 5 illustrates another modified form of sealing means in which an L-shaped sealing ring of reinforced rubber is employed. This ring includes an angular metallic reinforcing member 28 around which is molded a body of rubber or similar material 29. The reinforcing member 28 gives the desired stiffness to the ring, which is supported in position by being clamped between the portions 55 30 and 31 of the pump housing. In this instance, the sealing ring is adjusted to provide the proper clearance at the joint 32 between the inner periphery of the impeller disc 8 and the sealing face of the ring. By tightening or loosening the clamping bolts 31' the molded rubber will compress or expand and the desired clearance at the joint 32 may thus be readily obtained.

In Figure 6 I have illustrated a modified form of sealing ring which is particularly adapted to seal the joint between the outer periphery of the impeller 2 and the housing 4. This installation is generally similar to that shown in Figure 3 and includes a sealing ring 35 of rubber or similar flexible material, mounted in a groove 36 in the 70 housing 4. The face 37 of the ring 35 is adapted to engage the impeller disc 8 adjacent its outer periphery. The groove 36 is connected to a passage or plurality of passages 38 extending from the groove 36 into the clear-water space 12. 75

Thus, communication is established between the clear-water chamber and the back side of the sealing ring 35. Fluid pressure within the clear-water chamber will be applied to tend to flare 5 the lips 38 outwardly to maintain them in sealing contact with the sides of the groove 36 and exert a force on the sealing ring 35 tending to maintain the sealing face 37 in contact with the impeller 8. The operation of this form of my invention 10 is substantially the same as that described with reference to Figure 3.

When the pressure of the flushing liquid within the chamber 12 is greater than that within the main pumping chamber the flushing liquid will 15 be forced out through the lubricating grooves 35', thus lubricating the engaging surfaces and preventing the entry of harmful abrasive material to the clearance spaces. Even if the pressure within the main pumping chamber should 20 become greater than that within the auxiliary flushing water chamber the sealing ring 35 will be maintained in engagement with the impeller disc 8 and back flow of abrasive-containing liquid from the main pumping chamber into the 25 auxiliary chamber will be largely prevented.

In Figure 8 I have illustrated another form of my sealing ring construction in which the sealing ring 40 is adapted to be maintained in sealing contact with the impeller 8 by means of the 30 screws 41. Lock nuts 42 are preferably provided to maintain the screws in the desired position. A number of screws may be disposed circumferentially around the housing and, by tightening or loosening these screws, the desired sealing engagement 35 between the ring 40 and the impeller 8 will be obtained. A metallic backing ring 43 is preferably inserted between the inner ends of the screws 41 and the rubber sealing ring member.

40 From the above description it will be seen that my improved sealing ring construction provides an inexpensive and efficient means for preventing the entry of harmful foreign material into the clearance spaces between the impeller and the housing of a centrifugal pump and, although 45 I have described in some detail the forms of my invention which are illustrated in the drawing, it will be understood that modifications and variations may be made without departing from the 50 spirit of my invention. I do not, therefore, limit myself to the precise forms shown and described, but claim as my invention all embodiments thereof coming within the scope of the appended 55 claims.

55 I claim:

1. A centrifugal pump comprising a pump casing having a volute, an impeller rotatable in the casing and spaced from the latter to form a clear water pressure chamber on one side thereof, said 60 chamber having an annular outlet at its outer periphery into the volute, means for supplying clear water under pressure to said chamber, and sealing means for preventing entry of liquid into said chamber thru said annular outlet, said sealing 65 means comprising an annular rubber ring mounted in an annular groove in the casing adjacent to the said chamber outlet and having a side face pressing thruout its circumferential length against the side of the impeller at all times with liquid sealing pressure to prevent passage of water thru the annular outlet into the chamber, said ring having a portion distorted laterally with respect to the remainder thereof by contact of the 70 impeller with said face when the impeller and ring are in assembled position, and said distorted 75

portion being movable away from the impeller only under the influence of water under pressure in the chamber to permit escape of such water between the member and impeller.

2. A centrifugal pump comprising a pump casing having a volute, an impeller rotatable in the casing and spaced from the latter to form clear water pressure chambers on opposite sides thereof, each of said chambers having an annular outlet at its outer periphery into the volute, means 5 for supplying clear water under pressure to said chambers, and sealing means for preventing entry of liquid into said chambers thru said annular outlets, said sealing means comprising annular, rubber rings, mounted in annular grooves in the 10 casing adjacent to the said chamber outlets, each ring having a side face pressing thruout its circumferential length against the side of the impeller at all times with liquid sealing pressure to prevent passage of water thru the annular outlets into the chambers, said rings having portions distorted laterally with respect to the remainder thereof by contact of the impeller with said faces when the impeller and distorted portions are in assembled position, said rings being movable away 15 from the impeller only under the influence of water under pressure in the chambers to permit escape of such water between the rings and impeller, one of said chambers having an outlet opening into the suction side of the pump and 20 means to impede escape of water from the chamber thru said outlet.

3. A centrifugal pump comprising a pump casing part having a volute, an impeller part rotatable in the casing part and spaced from the latter 35 to form a clear water pressure chamber on one side thereof, said chamber having an annular outlet at its outer periphery into the volute, means for supplying clear water under pressure to said chamber, and sealing means for preventing entry of liquid into said chamber thru said annular outlet, said sealing means consisting of a rubber member carried by one of the said pump parts and having an annular portion disposed adjacent to the said chamber outlet, said annular portion 40 having a side face pressing thruout its circumferential length against the other said pump part at all times with liquid sealing pressure to prevent passage of water thru the annular outlet and into said chamber, said annular portion being 45 distorted laterally with respect to the remainder of the rubber member by contact with the other said pump part when the said part and rubber member are in assembled position and said annular portion being movable away from the other 50 said pump part only under the influence of water under pressure in the chamber to permit escape of such water between the member and the other said pump part.

4. A centrifugal pump comprising a pump casing part having a volute, an impeller part rotatable in the casing part and spaced from the latter to form clear water pressure chambers on opposite sides thereof, each of said chambers having an annular outlet at its outer periphery into the 65 volute, means for supplying clear water under pressure to said chambers, and sealing means for preventing entry of liquid into said chambers thru said annular outlets, said sealing means consisting of rubber members, each member being separate and distinct from the other member, being carried by one of said pump parts and having an annular portion disposed in the casing adjacent to its respective chamber outlet, each annular portion having a side face pressing thruout 70

its circumferential length against the other said pump part at all times with liquid sealing pressure to prevent passage of water thru the annular outlets into the chambers, each said annular portion being distorted laterally with respect to the remainder of the rubber member by contact with the other said pump part when in assembled relation therewith, and said annular portion being movable away from the other said

pump part only under the influence of water under pressure in its chamber to permit escape of such water between the member and the other said pump part, one of said chambers having an outlet opening into the suction side of the pump, and means to impede escape of the water thru the chamber of said outlet. 5

FRANK B. ALLEN.
